UNITED STATES PATENT OFFICE.

HENRY W. GONIA, OF BERWIND, WEST VIRGINIA.

GUARD FOR ELECTRIC CONDUCTORS.

1,099,744.

Specification of Letters Patent.

Patented June 9, 1914.

Application filed October 25, 1913. Serial No. 797,251.

To all whom it may concern:

Be it known that I, HENRY W. GONIA, a citizen of the United States, residing at Berwind, in the county of McDowell and State of West Virginia, have invented certain new and useful Improvements in Guards for Electric Conductors, of which the following is a specification.

The present invention relates broadly to improvements in protective devices and in particular to a guard designed to coöperate with a support for said conductor whereby to effectively protect against accidental contact with the conductor while at the same time permitting unobstructed use of the same for the usual purposes.

More specifically, my invention comprehends the employment of a yieldable guard freely swung from a trolley hanger, which hanger normally insulates the guard, the latter being adapted upon contact therewith, say by the head of a person passing beneath, the conductor to move or swing laterally into a position covering the wire, from which position it returns to its normal pendant position after the passage of the person therebeneath.

The particular advantages of my invention above described may be more readily appreciated when it is explained that it is designed for use in conjunction with electric conductors employed in mines where said conductor is disposed at a height liable to permit contact with the conductor of the heads of persons passing beneath the same. It is compulsorily required to protect these conductors especially at cross-overs in the mines or at points where diverging branches lead from the main tunnel and it has been the practice heretofore to drill a plurality of openings in the ceiling of the mines parallel with the main line conductor inserting supports in said openings and attaching to said supports the stationary guards or guard members such as boards nailed at intervals. This method, in most instances, necessitates some little expense first in the drilling of the holes for the inserting of the supports for the guard and it also makes the repair of such guard members difficult when once they have become broken. Again where the guard members are disposed as just described, in spaced relation to the conductor passing therebetween, a person rising to an upright position beneath the electric conductor is liable to have his head guided into

contact with the live wire if the head should touch one of the guard members directly therebeneath. To eliminate these disadvantages and possibilities, I have designed the invention which will be more fully understood by reference to the following description, and to the drawing wherein:

Figure 1 is a top plan view of my invention as applied to protect the electric conductors at the conjunction of a branch with the main tunnel in a mine; and Fig. 2 is an end elevation showing more clearly the details of construction, and in dotted lines the manner in which the guard members coöperate with the conductor to protect the same.

Throughout the following detail description and on the several figures of the drawings, similar parts are referred to by like reference characters.

Specifically describing my invention A designates the electric conductor for the main tunnel of a mine and B the branch conductor.

C, C, and C', C', designate a plurality of trolley supports or hangers disposed at proper intervals to maintain the electric conductors in proper positions as customary. Upon each of the hangers C, C, of the main electric conductor is disposed a horizontal cross-piece 1 which has formed centrally therein an opening to permit the disposition of the cross piece upon the insulating member D of the hanger, said cross piece at its extremities being bent vertically at 2 and from these bent ends are pivotally suspended strap members 3. To the corresponding strap members at each side of the electric conductor A are secured in any desired manner the guard members 4, in this instance boards, or it will be understood that the guard members 4 may be of any desired non-conducting material.

As will be clearly seen from the figures of the drawings, the guard members are disposed in spaced relation at each side of both the main electric conductor and the branch, the extrémités of the guards for the branch wire being suitably spaced from its contiguous guard member of the main branch to permit movement of said guard members. These guard members are free to swing laterally so that as a car turns into the branch tunnel the head of an occupant of the car in the event such occupant should be in such a position as to permit of contact with the

main wire will first strike the outer guard member 4 which will yield until it comes into a position contacting with the electric conductor A and in such position will protect the head of the occupant from contacting with the wire, it being understood that the guard members 4 are pendant a suitable distance lower than the conductor. The occupant is, therefore, protected from injury and after having passed into the branch tunnel, should it be desired to move in the opposite direction, contact with the same main wire is effectively prevented by the interposition of the guard member 4 at the opposite side of the main wire A operating in a manner described with reference to the first mentioned guard member.

Since the cross piece 1 is located above the insulating member D of the hanger support each of the guard members 4 is insulated from the cooperating wire conductor. On account of their free swinging connection with the cross piece 1, the guard members return to their normal vertically pendant position when contact with said members is discontinued. It is furthermore to be observed, in conclusion, that by the employment of the cross piece support cooperating with the hangers for the conductors, it is unnecessary to provide any suspension means other than those that are required for the maintenance of the conductors themselves in operative position.

Having thus described my invention, what I claim as new is:

1. In a protective device of the class described, the combination with a support for

an electric conductor, of a guard suspended from said support and comprising a movable member adapted to swing into guard, 40 coöperation with the conductor, said conductor limiting the swinging movement of the member.

2. In a protective device of the class described, the combination of a support, an electric conductor, a guard suspended from said support and comprising pendant members normally spaced from the conductor to permit free access thereto and yieldable toward the conductor for protection therefrom upon contact of an object with the said spaced members moving transversely across the path of said conductor.

3. In a protective device of the class described, the combination of supports, an electric conductor, a guard suspended from said supports and comprising a pair of cross pieces disposed upon a pair of the supports, each of said cross pieces extending at right angles to the conductor and having its extremities bent downwardly, strap members pivotally secured to the bent extremities of the cross pieces, and guard members of non-conductive material connecting the corresponding strap members at each side of the conductor, said guard members being freely movable toward the conductor and extending therebeneath.

In testimony whereof I affix my signature in presence of two witnesses.

HENRY W. GONIA.
